(57) CLAIM

The ornamental design for a frog boat incense burner, as shown and described.

DESCRIPTION

FIG. 1 is a perspective view of a frog boat incense burner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The portions of the frog boat incense burner shown in broken lines form no part of the claimed design.
